US00D944038S

(12) **United States Design Patent** (10) **Patent No.:** **US D944,038 S**
Oxnard (45) **Date of Patent:** **** Feb. 22, 2022**

(54) **ANIMAL SHAPED BLANKET**(71) Applicant: **Fuzzie Dot, LLC**, Yorba Linda, CA
(US)(72) Inventor: **Kristin Oxnard**, Yorba Linda, CA (US)(73) Assignee: **Fuzzie Dot, LLC**, Yorba Linda, CA
(US)(***) Term: **15 Years**(21) Appl. No.: **29/779,181**(22) Filed: **Apr. 16, 2021****Related U.S. Application Data**

(62) Division of application No. 29/732,747, filed on Apr. 27, 2020, now Pat. No. Des. 919,330, which is a division of application No. 29/720,751, filed on Jan. 15, 2020, now Pat. No. Des. 898,457, which is a division of application No. 29/643,741, filed on Apr. 11, 2018, now Pat. No. Des. 899,146.

CLAIM

The ornamental design for an animal shaped blanket, as shown and described.

DESCRIPTION

FIG. 1 is a front perspective view of an animal shaped blanket showing my new design;

FIG. 2 is a bottom view thereof;

FIG. 3 is a top view thereof;

FIG. 4 is a left-side view thereof;

FIG. 5 is a right-side view thereof;

FIG. 6 is a front view thereof; and,

FIG. 7 is a back view thereof.

The broken lines shown in the drawings are included for the purpose of illustrating unclaimed portions of the animal shaped blanket and form no part of the claimed design.

1 Claim, 7 Drawing Sheets
